UNITED STATES PATENT OFFICE.

GREENE CARLTON HOSCH, OF ST. LOUIS, MISSOURI.

PRESSER-ROLLER-RELEASING DEVICE.

1,394,554.

Specification of Letters Patent. Patented Oct. 25, 1921.

Application filed September 23, 1920. Serial No. 412,220.

To all whom it may concern:

Be it known that I, GREENE CARLTON HOSCH, a citizen of the United States, residing in the city of St. Louis and State of Missouri, have invented new and useful Improvements in Presser-Roller-Releasing Devices, of which the following is a specification.

This invention relates to measuring machines. Such machines usually embody in their construction, a measuring roller and a coöperating presser roller which presses the material being measured against the face of the measuring roller. As the material is pulled between the rollers, the measuring roller advances the indicating mechanism. With the presser roller a spring is associated that imparts its force to press the presser roller against the fabric lying between the rollers. Means is usually provided for detaining or latching the presser roller in a raised position in which it lies away from the face of the measuring roller; when in this position, an opening or gap is formed between the rollers to permit the introduction of the material to be measured. After the material or fabric to be measured has been introduced between the rollers, the operator of the machine then releases the presser roller, and its spring then forces it down upon the fabric or material to press the same against the measuring roller. When the presser roller is released in this way, the spring operates to drive it down against the measuring roller with considerable force, producing a more or less violent impact of the rollers. Such a violent impact between the rollers should be avoided, and the general object of the present invention is to provide a simple construction which will enable the presser roller to be released as usual, but which will operate in such a way that when released, the presser roller will descend by gravity upon the measuring roller, that is to say, the action of the spring on the presser roller is temporarily inhibited. After the presser roller has descended upon the measuring roller the action of the spring then becomes normal and exerts its force to press the fabric or other material against the face of the measuring roller. A further object of the invention is to construct the parts in such a way as to adapt them to use in a machine in which the presser roller is automatically raised by the action of the

knife which marks the edge of the material at the point where it is to be cut off. Although features of the invention are applicable to measuring machines of many types, for the purpose of illustration, in the present application, I have described the invention as applied to a fabric measuring machine.

Further objects of the invention will appear hereinafter.

The invention consists in the novel features, and in the general combination of parts to be particularly described herein-after, all of which contribute to produce a simple and efficient presser roller releasing device. A preferred embodiment of my invention will be particularly described in the following specification, while the broad scope of my invention will be pointed out in the appended claims.

In the drawing,

Fig. 1 is a side elevation of a fabric measuring machine embodying my invention;

Fig. 2 is a view similar to Fig. 1, but showing only the right hand portion of the machine, certain parts being broken away and shown in section;

Fig. 3 is a vertical section through the casing of the machine and passing through the releasing device as though taken about on the line 3—3 of Fig. 2;

Fig. 4 is a vertical cross section through the machine and further illustrating the releasing device; this view shows the parts in the relation which they have when the presser roller is disposed against the measuring roller;

Fig. 5 is a plan of the parts of the releasing device taken about on the line 5—5 of Fig. 4; and

Fig. 6 is a perspective illustrating the hand-actuated member that effects the release of the presser roller.

Referring more particularly to the parts, 1 represents the casing of a fabric measuring machine, one end of which is provided with a gap 2 into which the fabric may be introduced so that the fabric will lie between the measuring roller 3 and a presser roller 4 disposed above it (see Fig. 4). In applying my invention to such a machine, I mount the presser roller on a movable presser roller frame 5 which is preferably in the form of a rocking frame mounted to rock on pivots

or gudgeons 6 carried within the casing. Associated with this frame I provide a spring, the function of which is to press the presser roller against the measuring roller. 5 I also provide detent means for holding the presser roller frame in a position to hold the presser roller away from the measuring roller (see Fig. 3). In addition to this I provide releasing means for actuating the detent 10 means to permit the presser roller frame and its roller to descend by gravity upon the measuring roller; that is to say, the releasing means operates in such a way as to temporarily inhibit the action of the spring, the 15 normal function of which is to press the presser roller downwardly. In order to accomplish this I provide detent means including an arm 7 mounted near the middle point of a horizontal shaft 8, the ends of which 20 are supported in the inner frame 9 of the machine (see Fig. 2), and the presser roller frame 5 is provided with means to coöperate with this arm so that the arm may hold the presser roller frame in a raised position (see 25 Fig. 3); for this purpose the end of the detent arm 7 may be formed into a roller 10. Around the shaft 8 I provide a coil spring 11, one end of which is fixed at 12 and the other end of which extends over the forks 30 of the arm 7, which arm is preferably bifurcated as shown in Fig. 2 so as to receive the roller 10 between the forks. This roller 10 normally exerts pressure against a point on the rocker frame 5 above its pivotal axis 35 at 6 (see Fig. 4). The rocker frame 5 is constructed in such a way as to form a socket 13 which may receive this roller. This socket is most conveniently formed by providing a yoke 14, the upper edge 15 of which 40 lies adjacent to the upper edge of the rocker frame 5, but is bent away from the same as shown in Fig. 4. The arms 16 of this yoke support the presser roller 4 between them. With this construction, it will be evi- 45 dent that if the rocker frame is rotated in a clockwise direction (see Fig. 4), about its trunnion 6, the roller 10 will drop into the socket 13 and this will hold the presser roller elevated, as shown in Fig. 3. In order 50 to enable the presser roller to be raised and held raised in this manner, the rocker frame 5 may include an outwardly projecting arm 17 and this arm projects into the path of an edge 18 of the large knife lever 19 which 55 is pivoted at 20 and swings in the space 21 just inside the vertical wall 22 of the casing (see Figs. 2 and 4). When the knife lever is depressed by means of a thumb plate 23 carried near its end (see Fig. 1), the edge 60 18 of the lever will actuate the arm and latch the presser roller in its raised position. At the same time a knife blade 24 carried by this lever will coöperate with a fixed knife 25 to notch the edge of the fabric. 65 Fig. 1 shows the knife lever in a depressed

position which it assumes in marking the fabric at the point where it is to be cut off.

I provide a hand-operated member or actuating part for effecting the release of the rocker frame 5 from the detent means including the arm 7. This member is preferably mounted in such a way that it will engage and slightly raise the detent arm 7, thereby permitting the frame 5 to descend by gravity with its presser roller 4 onto the measuring roller. The actuating member then permits the detent arm to reengage the presser roller frame and impart the pressure of the spring to it. In order to accomplish this I prefer to provide the casing 1 with a 70 large rectangular notch 26 (see Fig. 1), which incidentally provides clearance for the thumb plate 23 when the knife lever is actuated. Just back of this notch 26 I provide an actuating plate which is preferably 75 in the form of a lever 27 supported on a hinge connection 27^a on the inner frame 9 of the machine. This plate is preferably offset forwardly (see Fig. 4) and its lower portion is provided with a cam face 28 which 80 may be carried on a V-shaped plate 29 secured to the inner face of the lever plate 27. In the raised position of the presser roller frame the cam face 28 lies against the outer and under face of the roller 10 on the end 85 of the arm 7. Now, if this plate 27 is pressed inwardly by the thumb of the operator the cam face 28 will produce a slight upward rotation of the arm 7 on the shaft 8, and this movement will be sufficient to 90 release the presser roller frame, which will then descend by gravity. When the operator removes his thumb from the lever 27 and permits it to hang freely, the spring 11 will then swing the arm 7 downwardly until 95 the roller 10 comes into contact with the outer side of the rocker frame 5. As soon as this occurs the spring pressure will be 100 imparted to the presser roller.

It is understood that the embodiment of 110 the invention described herein is only one of the many embodiments my invention may take and I do not wish to be limited in the practice of my invention nor in my claims, to the particular embodiment set forth.

What I claim and desire to secure by Letters Patent is:—

1. In a machine of the character described having a measuring roller, the combination of a presser roller, a movable presser roller above the measuring roller frame carrying the presser roller, a spring mounted to exert force on the presser roller frame and press its roller against the measuring roller, detent means coöperating with the presser roller frame to hold the same raised with the presser roller away from the measuring roller, and an actuating member coöperating with the detent means to inhibit temporarily 120 the action of the spring on the presser roller 125 130

frame to permit the presser roller frame and its roller to descend by gravity onto the measuring roller.

2. In a machine of the character described 5 having a measuring roller, the combination of a presser roller, a movable presser roller along the measuring roller frame carrying the presser roller, a spring mounted to exert force on the presser roller frame and press 10 its roller against the measuring roller, detent means coöperating with the presser roller frame to hold the same raised with the presser roller away from the measuring roller, and a hand-operated member having 15 a cam face for engaging the detent means and operating to inhibit temporarily the action of the spring on the presser roller frame to permit the same and the presser roller to descend by gravity onto the measuring roller.
- 20 3. In a machine of the character described, having a measuring roller, the combination of a presser roller, a movable frame carrying the presser roller above the measuring roller, detent means including a spring coöperating 25 with the presser roller frame to exert spring-pressure thereupon to hold the presser roller against the measuring roller, said presser roller frame and said detent means coöperating to hold the presser roller raised away 30 from the measuring roller, and a hand-operated part coöperating with the detent means to release the presser roller frame therefrom to permit the presser roller to descend by gravity onto the measuring roller.
- 35 4. In a machine of the character described, having a measuring roller, the combination of a presser roller, a pivotally supported presser roller frame carrying the presser roller above the measuring roller, detent 40 means including a spring, and a detent arm capable of coöperating with the presser roller frame to impart spring-pressure from the spring to the presser roller frame to press the presser roller against the measuring 45 roller, said presser roller frame having a socket to coöperate with the detent arm to hold the presser roller frame raised with its roller away from the measuring roller, and a hand-operated part for releasing the presser 50 roller frame from the detent arm to permit the presser roller to descend by gravity onto the measuring roller.
5. In a machine of the character described 55 having a measuring roller, the combination of a presser roller above the measuring roller, a presser roller frame carrying the same and mounted to rock on an axis, detent means including a spring and a detent arm, capable of coöperating with the presser roller 60 frame to impart spring-pressure from the spring to the pressure roller frame to press its roller against the measuring roller, said presser roller frame having a socket to coöperate with the detent arm to hold the 65 presser roller frame raised with its roller away from the measuring roller, and a hand-operated lever having means for moving the arm to disengage the same from the presser roller frame and thereby permit the presser roller to descend by gravity onto the measuring 70 roller.
6. In a machine of the character described, having a measuring roller, the combination of a presser roller, a presser roller frame carrying the presser roller above the measuring roller and mounted to rock on an axis, 75 detent means including a spring and a detent arm, capable of coöperating with the presser roller frame to impart spring-pressure from the spring to the presser roller frame to press its roller against the measuring roller, said presser roller frame having a socket to coöperate with the detent arm to hold the presser roller frame raised with its roller away from the measuring roller, and a hand-operated lever pivotally supported 80 above the detent means and having a cam face for engaging the arm to raise the same when the lever is actuated, and operating to disengage the arm from the presser roller frame to permit the presser roller frame to descend by gravity onto the measuring roller.
7. In a machine of the character described 85 having a measuring roller, the combination of a casing, a presser roller above the measuring roller, a presser roller frame carrying the same, mounted to rock on an axis within the casing, detent means including a spring capable of coöperating with the presser 90 roller frame to impart spring-pressure from the spring to the presser roller frame to press its roller against the measuring roller, said presser roller frame having means to coöperate with the detent means to hold the presser roller frame raised with its roller away from the measuring roller, said casing having an opening in the side wall thereof 95 opposite the detent means, and a lever pivotally mounted within the casing adjacent the opening for engaging said detent means to release the presser roller frame and permit the presser roller to descend by gravity onto the measuring roller.
8. In a machine of the character described, 100 having a measuring roller, the combination of a casing, a presser roller above the measuring roller, a presser roller frame carrying the same, mounted to rock on an axis within the casing, detent means including a spring 105 and an arm constrained by the spring and pivotally supported in the casing so as to project toward a side wall of the casing, said presser roller frame having means to coöperate with the arm to hold the presser 110 roller frame raised with its roller away from the measuring roller, said side wall of the casing having an opening opposite the arm, and a lever pivotally mounted within the casing adjacent the opening for engaging 115
- 120
- 125
- 130

the arm to move the same, and thereby release the presser roller frame from the detent arm and permit the presser roller frame to descend by gravity onto the measuring roller, said lever constructed to permit the detent arm to impart the force of the spring to the presser roller frame after the same has descended by gravity.

9. In a fabric measuring machine having 10 a measuring roller, the combination of a casing, a presser roller above the measuring roller, a presser roller frame carrying the same, and mounted to rock in the casing, a knife for marking the edge of the fabric, 15 and operating to rock the presser roller frame when the knife is actuated and thereby move the same into a raised position with

the presser roller away from the measuring roller, detent means including a spring and a detent arm coöperating with the presser roller frame to hold the same in the raised position, and a hand-operated member co-operating with the detent arm to move the same and thereby release the presser roller frame to permit the same with its roller to descend by gravity onto the measuring roller, said detent arm operating after the presser roller has descended, to impart the force of the spring to the presser roller frame. 20 25 30

In testimony whereof, I have hereunto set my hand.

G. CARLTON HOSCH.
